(57) **CLAIM**

We claim the ornamental design for sports goggles, as shown and described.

DESCRIPTION

FIG. 1 is a perspective view of a pair of sports goggles, seen from the front and left side thereof, showing our new design; FIG. 2 is a front view thereof; FIG. 3 is a left side view thereof, the right side being a mirror image thereof;

FIG. 4 is a bottom view thereof; and,

FIG. 5 is a top view thereof.

The broken line showing in the figures is for illustrative purposes only and forms no part of the claimed design.
